Inventor

FRANK SAUCIER,

By *James N. Cylas*

Attorney

UNITED STATES PATENT OFFICE.

FRANK SAUCIER, OF HAINES, TERRITORY OF ALASKA.

MEANS FOR ATTACHING CAPS AND FUSES TO STICK EXPLOSIVES.

Application filed August 4, 1921. Serial No. 489,809.

To all whom it may concern:

Be it known that I, FRANK SAUCIER, a citizen of the United States, residing at Haines, in the Territory of Alaska, have 5 invented certain new and useful Improvements in Means for Attaching Caps and Fuses to Stick Explosives, of which the following is a specification.

This invention relates to explosives in 10 stick form adapted to be exploded by concussion and it has for its object to provide improved means for attaching to or associating with such stick of explosive the detonating cap commonly employed for bringing about the explosion of the stick.

Many of the explosives of the stick type commonly employed in mining, quarrying and like work and of which dynamite constitutes the most familiar example, freeze at 20 comparatively high temperatures. In their frozen condition it is not possible to form a hole in them for the insertion of the detonating cap. It is, therefore, the common practice for miners and other persons using 25 explosives of this character, to thaw them out before use, and they must be thawed to very near the danger point before it is possible to form a hole in them for the reception of the detonating cap.

30 One of the important features of the present invention consists in making a preformed hole in the stick of dynamite or like explosive at the time of manufacture of such stick and in making the hole of such 35 configuration that a piece of fuse with the attached priming cap may be slipped thereto but cannot be withdrawn therefrom by a direct pull.

A subsidiary feature of the invention 40 resides in making the said preformed hole of such configuration that it will be operative for the purposes intended, even though the stick of dynamite be cut in two, transversely.

45 Further objects and advantages of the invention will be set forth in the detailed description which follows.

In the accompanying drawing:

Fig. 1 is a side elevation of a dynamite 50 stick constructed in accordance with the invention;

Fig. 2 is a longitudinal sectional view therethrough;

Fig. 3 is a rear end elevation thereof with 55 a closure cap in place;

Fig. 4 is an end elevation with the cap removed; and

Fig. 5 is a sectional view upon the line 5-5 of Fig. 2.

Like numerals designate corresponding 60 parts throughout the several figures of the drawing.

In the drawing 5 designates the usual heavy paper enclosing case, or wrapping, and 6 the more or less plastic explosive, 65 such as dynamite or the more or less solid explosive, such as blasting powder. It makes no difference as far as the principle involved is concerned, what particular kind of explosive is contained in the casing 5. 70 In carrying out the invention, I form in the explosive at the time of manufacture a hole 7 which extends longitudinally all the way through the stick and openings 8 which extends inwardly from the opposite ends of 75 the stick and lie in spaced relation to the opening 7, the openings 8 being of a depth to receive the cap 9. Transverse grooves 10 formed in the body of the explosive at the opposite ends of the stick connect the openings 7 and 8.

I, preferably, provide removable caps or closures 11, which enter the open ends of the casing 5 and seal the same, but which may be easily and quickly removed and replaced when it is desired to attach the fuse and cap to the explosive stick.

When the fuse and cap is to be attached to the stick, the closures 11 are removed and the fuse, with the cap 9 attached thereto, is passed longitudinally through the stick through the opening 7. The fuse is pushed through a sufficient distance to permit of its being given a return bend so that the cap 9 may be inserted in one of the 95 opening 8. The fuse 12 is then given a reverse pull which causes it to bind firmly in position and the cap 11 constituting the inner or lower end of the stick is replaced and the charge is ready for use.

When working in dry ground it is not absolutely essential that the cap 11 be replaced, but in working in wet ground, I contemplate using any suitable waterproofing material, such as tar, paraffin or the like, 105 inserting the same in the open end of the casing 5 and thereafter replacing the cap. If it be desired to seal the upper end of the stick, the cap at that end may be suitably notched for the passage of the fuse 12. 110

The purpose of providing two of the openings 8 is that the fuse may be inserted from either end of the stick and that there will still be an operative device, if the stick 5 is cut in two transversely to form a half charge. With some kinds of explosives I find it is desirable to insert paper tubes in the body of explosive material 6 during the process of manufacture, in order to aid in 10 forming the holes. Some explosives are sufficiently stiff after manufacture to permit of the removal of these paper tubes, but it is to be understood that the invention contemplates leaving these tubes in position, 15 when desired.

It will be seen that the present invention provides a very simple and economical construction for attaching a fuse and cap to an explosive stick whereby the use of 20 strings, wires and like ties is eliminated. Furthermore, the attachment of the fuse and cap to the stick may be very rapidly effected. In one mine with which I am familiar, employing forty miners, it required the entire time of three men to thaw 25 the powder, bore the necessary holes in the sticks of explosives and insert the fuse and primers, by the usual method. With the present invention, one man could do this 30 work in a comparatively short time.

It is a well known fact that workmen who have to spend considerable time in handling thawed powder and making the sticks ready for use as primers suffer from 35 severe headaches. My invention will in a large measure prevent this because of the very greatly reduced time required to do the work with the consequent reduction in the amount of handling of the dynamite 40 required.

It is to be understood that the invention is not limited to the particular construc-

tion shown, because other ways of arranging the hole will readily suggest themselves. The invention resides in providing 45 holes into which the fuse and cap may be slipped which are of such configuration that a reverse pull upon the fuse will not serve to withdraw the fuse and cap.

Having described my invention, what I 50 claim is:

1. An explosive stick having an opening formed therein for the passage of a fuse cap and an additional opening for the reception of the cap after the fuse has been given a 55 return bend, said stick being provided with a transverse recess at its end for connecting said openings, and a retaining casing for supporting the said stick.

2. An explosive stick having a fuse opening formed longitudinally therethrough and a pair of primer openings formed part way therethrough, the openings of said pair extending inwardly from the opposite end of the stick, said stick being provided with 65 transverse recesses at its opposite ends for connecting said fuse opening and said primer opening.

3. An explosive stick comprising a retaining casing and a filling of explosive 70 material there being a fuse receiving channel formed longitudinally entirely through said stick at one side thereof and a pair of openings extending longitudinally there- 75 of one at each end of the stick and at the opposite side of the stick from said channel, transverse recesses connecting said channel and said openings at the opposite ends of the stick, said last named openings terminating short of the center of the stick. 80

In testimony whereof I affix my signature.

FRANK SAUCIER.
